(57) **CLAIM**

I claim the ornamental design for a bag, as shown and described.

DESCRIPTION

FIG. 1 is a front perspective view of a bag; FIG. 2 is a front perspective, partially exploded view thereof;

FIG. 3 is a front side elevation view thereof;

FIG. 4 is a rear side elevation view thereof;

FIG. 5 is a right side elevation view thereof;

FIG. 6 is left side elevation view thereof;

FIG. 7 is a top plan view thereof; and,

FIG. 8 is a bottom plan view thereof.

The broken lines shown in the drawings are included for purposes of illustrating environment and form no part of the claimed design. The surface shading lines show contour and/or distinguish between open and solid areas. The surface shading lines are not surface ornamentation.
